OXIDES OF AMINO ACIDS

Max Engelmann, Wilmington, Del., assignor to
E. I. du Pont de Nemours & Company, Wil-
mington, Del., a corporation of Delaware

No Drawing. Application April 15, 1938,
Serial No. 202,358

13 Claims. (Cl. 260—404)

This invention relates to new and useful surface active materials. More particularly it relates to new pentavalent nitrogen compounds containing acidic groups which are superior to soap and soap substitutes. Still more particularly it relates to di-alkyl-oxamino long chain fatty acids and the salts thereof and processes for preparing the same.

It is an object of this invention to produce new and useful surface active materials which may be substituted for or used in admixture with various soaps and soap substitutes. A still further object is to produce new products which overcome many of the disadvantages of soap and soap substitutes. A still further object is to produce pentavalent nitrogen compounds which are of particular value as surface tension lowering, wetting, dispersing, penetrating, emulsifying and detergent agents. A still further object is to produce a class of compounds which may be used either alone or in admixture with one another and/or in admixture with soap and soap substitutes of the prior art for the numerous purposes wherein soap and soap substitutes of the prior art have been used or are capable of use. Still other objects will become apparent from a consideration of the following description and claims.

The above and other objects are accomplished in accordance with the herein described invention wherein dialkylamino long chain aliphatic carboxylic acids are reacted with oxidizing agents to produce dialkyloxamino aliphatic acids. The acids prepared may be represented by the following general formula:

wherein R_1 and R_2 represent aliphatic or cycloaliphatic hydrocarbon radicals, and R_3 is an aliphatic hydrocarbon radical containing an acidic group, e. g., a carboxylic or sulfonic acid group, at least one of the radicals represented by R_1 , R_2 and R_3 must have a chain length of at least 8 carbon atoms.

In a more limited sense the invention pertains to pentavalent nitrogen compounds containing a carboxylic acid group having the following general formula:

wherein one of the R 's represents an aliphatic hydrocarbon radical having a chain length of

at least 7 carbon atoms, R_1 represents an aliphatic or cycloaliphatic hydrocarbon radical containing not more than 6 carbon atoms, and R_2 is alkylene radical containing from 1 to 4 carbon atoms, and M represents hydrogen or a water soluble salt forming component.

In another valuable form of this invention the carboxyl group of the formula of the immediately preceding paragraph may be replaced by a sulfonic acid group and the R attached to R_2 is a hydrogen atom.

In its preferred embodiment this invention pertains to dialkyl-oxamino carboxylic acids and the salts thereof having the general formula:

wherein one R is an alkyl radical containing at least 7 and preferably 11 to 17 carbon atoms, and the other R is hydrogen and M represents hydrogen or a water soluble salt forming component, e. g., alkali or alkaline earth metals and organic amines, such as diethylamine, triethanolamine, etc.

The invention will be further illustrated but is not intended to be limited by the following examples in which the quantities stated are in parts by weight:

Example I

Thirty-one parts of alpha-dimethyl-amino-stearic acid which may be prepared by reacting alpha-brom-stearic acid and dimethyl-amine, 12 parts of hydrogen-peroxide-urea compound (Beilstein Vol. III, p. 54), and 150 parts of methyl alcohol are heated under reflux for 10 hours. The clear solution is then neutralized with 6 parts of a 20% aqueous solution of sodium hydroxide and evaporated on a steam bath to dryness. The crystalline product is a mixture of the sodium salt and the free dimethyl-oxamino-stearic acid. It is easily soluble in warm water, forming a very viscous solution. It is also soluble in methyl alcohol. Calcium or magnesium salt solutions or acids or alkalies do not form insoluble precipitates in aqueous solutions. It is a very effective scouring agent.

Example II

Fifty parts of alpha-dimethyl-amino-palmitic acid, 200 parts of ethyl alcohol, and 50 parts of hydrogen peroxide (27% aqueous solution), are boiled under reflux for 10 hours. After cooling, a small part of unreacted amino-acid is filtered off, the filtrate neutralized with sodium hydrox-

ide solution and the alcohol evaporated on a steam bath. The residue, containing dimethyl-ox-amino palmitic acid, shows very similar properties as the corresponding stearic acid derivative.

5 *Example III*

10 Sixty parts of ammonium persulfate are dissolved in 125 parts of a 20% aqueous sulfuric acid solution and mixed with 50 parts of alpha dimethyl-amino-stearic acid. The mixture, kept at room temperature, is slowly converted into a paste-like mass. After standing for 48 hours, it is neutralized with 170 parts of 20% sodium hydroxide solution. The resulting product is a 15 gelatinous paste, containing as active ingredient dimethyl-oxamino-stearic acid.

15 In place of the specific oxidizing agents of the preceding examples any of the usual types of oxidizing agents which are capable of liberating free oxygen may be used. Other agents which 20 may be substituted are per mono-sulfuric acid (Coro's acid) organic peroxides, e. g., benzoyl-peroxide, sodium hypochlorite, etc.

20 In place of the dialkyl-amino fatty acids of the preceding examples, any acid which complies with the instructions set forth in the above formulae may be substituted. As further examples of such acids may be mentioned diethyl- α -amino myristic acid, dimethyl α -amino palmitic acid, methyl-hydroxyethyl α -amino lauric acid, dibutyl α -amino capric acid. Mixtures of alkyl or hydroxyalkyl fatty acids obtained from natural oils or fats such as coconut oil, palm oil, lard, etc. The class of compounds may be prepared by alkylating α -amino long chain fatty acids, e. g., α -aminolauric acid, α -aminostearic acid α -methylamino palmitic acid, etc. with an alkylating agent in the usual manner, e. g., with methyl or ethyl chloride, dimethyl sulfate, sodium 35 butyl sulfate, ethylene oxide, propylene oxide, cyclohexyl chloride, etc.

35 Another series of dialkyl-amino long chain fatty acids which may be used are those which may be prepared, for example, by reacting a long 40 chain secondary amine with a halogenated aliphatic acid, preferably a carboxylic acid. Amino acids of this type are methyl-stearyl-aminoacetic acid, propyl-lauryl-aminobutyric acid, octylhydroxyethyl amino-valeric acid, methyl-decyl-aminoethane-sulfonic acid, ethyl heptadecylamino propane sulfonic acid, etc.

45 The long chain radicals present in the oxamino acids can be derived from animal and vegetable oils or fats or from crude mineral oils (naphthenic acids) or from carboxylated or aminated natural or synthetic long-chain hydrocarbons.

50 The uses of the compounds embraced within the scope of this application are legion and since 55 they are of chief value because of their surface active properties, no detailed description here is deemed essential. However, in order to exemplify the value of the products in the arts, a mention of a few uses will follow. For example, they may be used alone or in combination with other suitable detergents for cleansing and scouring vegetable and animal fibers when removing fatty or oily materials. They may be used as penetrants in acid solutions which are used for carbonizing 60 vegetable matter in wool. When added to flax retting baths, they function as wetting and penetrating agents. They may be employed as assistants in fulling and felting processes. They may be used in sizing preparations in combination 65 with the usual materials such as starches or gela-

70 tine or their equivalents, clays, talcs or their equivalents, weighting salts such as magnesium sulfate or calcium chloride, oils and oils processed by oxidation, polymerization, sulfonation, etc. The penetrating power of these new compositions 75 is utilized with advantage when they are added to baths containing starch ferment which are employed for removing sizing from textile materials. These products function as useful wetting, cleansing, and penetrating agents in bleaching 10 liquors such as those used in the kier boiling of cotton goods. They may be added to the lye liquors used for mercerizing cotton goods. They improve the absorption capability of fibrous materials when such materials are subjected to 15 treatments for finishing, softening, stiffening, coloring, preshrinking, impregnating, waterproofing, and mildew-proofing. They may be used alone or in combination with other materials for lustering or delustering fabrics. They may be 20 employed to oil or lubricate textile materials and as assistants in processes of weighting or loading fabrics. They may be used as assistants in silk degumming liquors and silk soaking solutions. They can also be used to assist in twist setting in 25 yarn and in processes of stripping colors. These compounds may be used as assistants in processes of stripping dyes from dyed textile materials.

30 Another important class of uses of these new compositions is as assistants in the preparation 30 and application of dyestuffs. They may be used in the preparation of dyestuffs in readily dispersible form and for the production of inorganic pigments or pigments or azo, basic, acid, vat, and sulfur dyes in a finely divided condition. As 35 penetrants and wetting agents they assist in producing level dyeings in neutral, acid or alkaline dyeing baths. They facilitate dyeing with developed dyes, the dyeing of animal fibers with vat dyes, the dyeing of cellulose acetate fibers 40 with insoluble dyes, dyeing and printing with aniline black, and the dyeing of leather. In printing pastes they assist in the dispersion of the dye or dye component and facilitate its penetration into the natural or synthetic fiber. Solutions of 45 these compounds are useful for increasing the fastness of dyeings on textile materials. Solutions of these compounds may be used for increasing the affinity of textile fibers of vegetable origin for acid-chrome dyestuffs. These 50 compounds may be used as assistants in resist printing processes.

55 In the leather industry these compositions function as useful wetting agents in soaking, deliming, bathing, tanning, and dyeing baths. They are useful in softening and treating baths for 60 hides and skins, particularly in baths used for fat-liquoring leather and in processes of waterproofing leather. Solutions of these compounds are useful for pretreating leather prior to dyeing.

65 The dispersing and emulsifying powers of these new compositions give rise to many interesting uses. They may be utilized for converting liquid or solid substances normally insoluble in water, such as hydrocarbons, higher alcohols, pitches and pitchy substances into clear solutions or stable emulsions or dispersions. They are useful in preparing emulsions of wax and 70 wax-like compositions which are used as leather dressings or floor polishes. They may be used to prepare artificial dispersions of crude, vulcanized or reclaimed rubber. They may be used as emulsifiers in the manufacture of cosmetic preparations such as cold creams and lip sticks. 75

They may be employed for preparing emulsions of the water-in-oil type such as emulsions of water in such organic solvents as are used in the dry cleaning industry. They are also of value in the breaking of petroleum emulsions, such as those naturally occurring in nature or produced during the refining of petroleum.

These compositions may also be used alone as bactericides and contact insecticides and for enhancing the spreading and penetrating power of other parasiticides. They may be employed in agricultural sprays in combination with the ordinary insecticides and fungicides. They are useful for promoting the penetrating power of wood preservatives.

In the paper industry these products may be used as penetrants in the liquors used for cooking rags and pulp, and as assistants in paper softening, filling, and processes to increase absorbency.

These compositions may be employed as detergents in several different relations. They may be used in the washing of fruits and vegetables for spray residue removal. They may be used in combination with metal cleaning compounds in neutral, acid, or alkaline liquors. They may be used for paints, varnish, and lacquer cleaners. They may advantageously be employed as cleansing agents in hard water and where a fatty or oily film resists the ordinary cleansing media. They may be added to soap in acid or hard water baths, since these compositions do not form precipitates so readily in hard and acid waters as soaps and Turkey red oils.

These compositions may be used as aids in various chemical reactions. They may be used to control particle size and shape during precipitation or crystallization of compounds from reaction mixtures. They may be used to decrease the particle size of insoluble amine hydrochlorides just before these amines are to be diazotized.

These compositions also have several miscellaneous uses. They may be employed as foam stabilizing agents, especially for use in air-foam fire extinguishing compositions. They may be used to stabilize rubber latex. They may also be used as frothing and collecting agents in ore flotation processes, and in other processes such as the recovery of fixed oil from the oil sands. The uses mentioned will suggest many similar ones.

By means of the present invention a large class of new and commercially feasible surface active materials has been rendered available for use. These compounds possess satisfactory colloidal properties and are of particular value for use in place of or in combination with soap and soap substitutes. This invention is of considerable interest in that the reactants which enter into it are for the most part readily available at a relatively low cost. The large variety of reactions which may be relied upon permit considerable latitude in the selection of reactants and the conditions of reaction. Likewise, the large number of compounds embraced within this category permit the selection of individual members thereof for a wide variety of purposes. In other words, where high wetting and dispersing properties are of paramount importance the molecular weight of these compounds may be lowered. On the other hand, where detergent properties are of primary interest the molecular weight of the compounds may be increased.

As many apparently widely different embodiments of this invention may be made without de-

parting from the spirit and scope thereof, it is to be understood that the invention is not limited to the specific embodiments thereof except as defined in the appended claims.

I claim:

1. The new products of the formula:

5

10

wherein R_1 and R_2 represent a radical selected from the group consisting of aliphatic and cycloaliphatic radicals, and R_3 is an aliphatic hydrocarbon radical containing an acidic group and at least one of the radicals represented by R_1 , R_2 and R_3 has a chain length of at least 8 carbon atoms.

2. The new products of the formula:

20

wherein R_1 and R_2 represent a radical selected from the group consisting of aliphatic and cycloaliphatic radicals and R_3 is an aliphatic hydrocarbon radical containing a monobasic acidic group and at least one of the radicals represented by R_1 , R_2 and R_3 has a chain length of at least 8 carbon atoms.

3. The new products of the formula:

30

wherein R is an alkyl radical containing at least 7 carbon atoms, R_1 is a hydrocarbon radical selected from the group consisting of aliphatic and cycloaliphatic hydrocarbon radicals containing not more than 6 carbon atoms, R_2 is an alkylene radical containing from 1 to 4 carbon atoms, and X is an acid group selected from the class consisting of sulfonic and carboxylic acid groups.

4. The new products of the formula

45

wherein one R is an alkyl radical containing at least 7 carbon atoms and the other R is hydrogen, R_1 is a hydrocarbon radical selected from the group consisting of aliphatic and cycloaliphatic hydrocarbon radicals containing not more than 6 carbon atoms, R_2 is an alkylene radical containing from 1 to 4 carbon atoms, and M represents a member of the group consisting of hydrogen and a water soluble salt forming group.

5. The new products of the formula

60

wherein one R is an alkyl radical containing at least 7 carbon atoms and the other R is hydrogen, R_1 is a hydrocarbon radical selected from the group consisting of aliphatic and cycloaliphatic hydrocarbon radicals containing not more than 6 carbon atoms, and M represents a member of the group consisting of hydrogen and a water soluble salt forming group.

70

6. The new products of the formula

75

wherein one R is an alkyl radical containing at least 7 carbon atoms and the other R is hydrogen, R₁ is an aliphatic hydrocarbon radical containing not more than 6 carbon atoms, and M represents a member of the group consisting of hydrogen and a water soluble salt forming group.

7. The process which comprises reacting an amino acid of the formula:

10

wherein R₁ and R₂ represent a radical selected from the group consisting of aliphatic and cyclo-aliphatic radicals, R₃ is an aliphatic hydrocarbon radical containing an acidic group and at least one of the radicals represented by R₁, R₂ and R₃ has a chain of at least 8 carbon atoms with an oxidizing agent.

20 8. The process which comprises reacting an amino acid of the formula

25

wherein R₁ and R₂ represent a radical selected from the group consisting of aliphatic and cyclo-aliphatic radicals, R₁ is an aliphatic hydrocarbon radical containing an acidic group and at least one of the radicals represents by R₁, R₂ and R₃ has a chain of at least 8 carbon atoms with an oxidizing agent containing free oxygen.

9. The process which comprises reacting an amino acid of the formula

35

40 wherein R₁ and R₂ represent a radical selected from the group consisting of aliphatic and cyclo-aliphatic radicals, R₃ is an aliphatic hydrocarbon radical containing an acidic group and at least

one of the radicals represented by R₁, R₂ and R₃ has a chain of at least 8 carbon atoms with a peroxide.

10. The process which comprises reacting an amino acid of the formula

wherein one R is an alkyl radical containing at least 7 carbon atoms and the other R is hydrogen, R₁ is a hydrocarbon radical selected from the group consisting of aliphatic and cycloaliphatic hydrocarbon radicals containing not more than 6 carbon atoms, and R₂ is an alkylene radical containing from 1 to 4 carbon atoms with an oxidizing agent containing free oxygen.

11. The new products of the formula

wherein one R is an alkyl radical containing at least 7 carbon atoms and the other R is hydrogen, and M represents a member of the group consisting of hydrogen and a water soluble salt forming group.

12. The new products of the formula

wherein R is an alkyl radical containing from 11 to 17 carbon atoms and M represents a member of the group consisting of hydrogen and a water soluble salt forming group.

13. Alpha-dimethyl-oxamino stearic acid which has the formula

MAX ENGELMANN.
